UNITED STATES PATENT OFFICE.

THEODORE PAROBI, OF DUNDEE LAKE, NEW JERSEY.

SMOKE-CONSUMER.

1,273,402.

Specification of Letters Patent. Patented July 23, 1918.

Application filed April 13, 1917. Serial No. 161,697.

To all whom it may concern:

Be it known that I, THEODORE PAROBI, a subject of the Emperor of Austria, resident of Dundee Lake, county of Bergen, and 5 State of New Jersey, have invented certain new and useful Improvements in Smoke-Consumers, of which the following is a specification.

This invention relates to improvements in 10 smoke-consuming apparatus and has for its object the provision of a simple, efficient, and inexpensive device of this character wherein a pipe of novel construction is located in the smoke stack, and is provided 15 with a series of burner tubes adapted to be supplied with a gasoline heating medium by a manually-controlled means within control of the locomotive engineer.

A further object of this invention relates 20 to the provision of a smoke-consuming device wherein any increase in the force of the draft within the smoke stack of a locomotive will result in the automatic feeding of a correspondingly increased amount of gasoline 25 to the burners which consume the unburnt particles of carbon that may be passing through the smoke stack.

With the above and other objects in view 30 my invention consists in the combination, construction and parts disclosed in the drawings and specification, and then more particularly pointed out in the appended claims.

In the drawings, wherein similar reference characters designate similar parts 35 throughout the several views,

Figure 1 is a fragmental side elevational view of a locomotive showing the application of my invention,

Fig. 2 is an enlarged fragmental side elevational view of a portion of the same,

Fig. 3 is a similar view showing a modification in construction,

Fig. 4 is a fragmental sectional view showing one of the burners,

Fig. 5 is a similar view showing a modified form of the burner to be described,

Fig. 6 is a detail sectional view showing the application of the invention to the smoke stack,

Fig. 7 is a detail sectional view taken through the smoke stack in another plane,

Fig. 8 is a transverse sectional view taken on line 8—8 of Fig. 6, and

Fig. 9 is an enlarged sectional view showing the valve construction.

In order to fully consume the particles of

carbon, sulfur, and the like emanating from a partially consumed fuel within a furnace, it is found necessary to bring the same into direct connection with an extremely hot fire 60 before passage into the atmosphere, and I have found it desirable to control this hot fire by the variation in the force of the draft through the smoke stack, thereby further rarefying the air currents and producing 65 an updraft which assists materially in the combustion of the fuel used in the furnace as well as completely consuming any particles rising therefrom.

In Fig. 1 is shown an illustration of an 70 ordinary locomotive 10 having a smoke-stack 11 and upon the upper portion of the boiler is attached, contiguous to the stack, a reservoir or tank 14 having at the top a filling nozzle 15, and provided with a sight gage so 75 that the quantity of liquid fuel contained within the reservoir may be seen.

Entering the reservoir 14 is a pipe 18 connecting with a pump 19 actuated by a handle 20 by means of which air may be forced into 80 the tank, thereby supplying a desirable pressure.

At the bottom of the tank, which may be secured by supports or brackets 21, directly to the smoke stack 11, or by bands 22 (as 85 shown) is engaged a pipe 25 which may be formed into a coil, if desired, so as to avoid danger of separation due to strain, the pipe ultimately entering the lower part of the smoke stack and having connected thereto a 90 valve body 27 secured to the locomotive. This valve body 27 forms a part of the fuel conduit or pipe 25 and the passage through the valve chamber is controlled normally by means of the conical plug 28 pressed against 95 the seat formed in the body 27 by means of the coiled push spring 29.

It will be noticed that the valve body 27 has its vertical passage 50 communicating with a conical transversely-extending bore 100 51, and that the conical plug 28 terminates in a polygonal rod or stem 52 slidably mounted in the valve body. This plug 28 has one end of the spring 29 bearing against it so as to force it to engage the conical seat 105 of the bore 51, but from Fig. 9 it will be seen that the conical plug 28 is spaced, when in closed position, from the inner conical wall of the bore 51 so that a minimum amount of gasoline will, at all times, pass up through the passage 50 to the rings 38 and 39 which, upon becoming heated by the products of 110

combustion or smoke rising unconsumed through the smoke stack 11, ignite the gasoline. The locomotive engineer is at all times able to control the flow of gasoline manually 5 to the burner by increasing the air pressure within the initial gasoline reservoir 14 as the hand pump 19 is placed within immediate access and control of the engineer. Connected to the plug 28 is a stem 30 carrying at its outer end the angularly-disposed plate 32. The pipe 25 extends upwardly within the smoke stack and is secured in position eccentrically therein by means of the clips 37 secured to the inner wall of the smoke-stack. Formed integrally upon this pipe 25 are a series of coils or ring-like burner members 38 and 39 which are horizontally disposed within the smoke stack so as to be positioned within the greater part 15 of the space of the smoke stack.

Both of the rings 38 and 39 have radial tubes 42 terminating in burners 43 as indicated in Figs. 4 and 8, or double burners 45 as shown in Fig. 5. These burner tips are 25 arranged to project radially of each annular burner member 38 and 39, toward the center thereof so that the flames and heated gases emanating from these burner tips will thoroughly commingle with the smoke or unconsumed particles of carbon issuing up through the smoke stack and be burnt up.

From the foregoing it will be seen that I have provided a simple, and effective burner device heated by means of gasoline fed from an initial source of gasoline supply. The locomotive engineer will initially pump air into the reservoir 14 containing the gasoline which will gradually be forced up through the pipe 25, in small quantities into the burner tips, owing to the pressure in the tank 14, as there will necessarily be vapor pressure in the coils of pipe 25; it will be noticed that the burner tubes project flames to intercept the continued passage of the 40 products of combustion or smoke; when there is any increase in the force of fluid pressure within the smoke stack such as is due to the exhaust from the engine the force of fluid pressure acting in the smoke stack will cause the plate 32 to move inwardly, thus unseating the plug 28 and causing the inlet for the gasoline controlled by this plug to become enlarged whereby more gasoline will be fed to the burner tubes and more heat generated. 50 When the fluid pressure falls within the stack, the difference in the atmospheric pressure and this pressure will result in a draft and whatever smoke or unconsumed particles

of carbon will then rise through the smoke stack will, upon coming into contact with 60 the highly heated burner tubes be consumed in a very effective manner. By increasing the air pressure within the initial gasoline tank 14, the engineer can, at any time cause a greater amount of gasoline to be forced up 65 through the pipe 25 to the burner tubes, even when the plug 28 is in seated position so that the burner members may be kept heated at all times, so long as there is gasoline within the reservoir 14.

Numerous modifications may be resorted to in practice without departing in details from the principle of invention herein disclosed.

What I claim and seek protection on is:— 75

1. In a smoke-consuming device, in combination, with a smoke stack, a fuel supply tank contiguous thereto, and means for supplying pressure within said tank, a pipe in said smoke stack, a valve on said pipe in 80 said smoke-stack controlling the passage through said pipe, means actuated by the discharge of gases through said smoke-stack to open said valve, and a plurality of burners having one or more orifices arranged within 85 said smoke-stack, said pipe leading from said tank to said burners.

2. In a device as described, in combination, a smoke stack, a gasoline reservoir disposed alongside thereof, a burner feed pipe 90 extending vertically within said stack and having its lower portion projecting through the side of said stack so as to be connected to the lower end of said gasoline reservoir, a valve chamber interposed in the length of 95 said burner feed pipe and providing a passage through said pipe, a plug fitting said passage so as to normally be seated, but shaped so as to allow a portion of said passage to remain open, a spring in said valve 100 chamber adapted to be compressed when said plug is forced thereagainst in order to increase the opening of said passage, and a draft-pressure operated plate adapted to actuate said plug.

3. In a device as described, in combination, a smoke-stack, a liquid fuel supply tank, a feed pipe leading from said tank into said smoke stack and formed thereon with burners, said pipe having a normally-restricted 110 passage, and means responsive to the impact of gases passing through said stack for increasing the size of said passage.

In testimony whereof I have affixed my signature.

THEODORE PAROBI.
